UNITED STATES PATENT OFFICE.

EUGENE HUREZ, OF PETIT COURONNE, NEAR GRAND COURONNE, FRANCE.

REGENERATIVE FURNACE.

1,333,716.

Specification of Letters Patent. Patented Mar. 16, 1920.

Application filed March 19, 1917. Serial No. 155,887.

To all whom it may concern:

Be it known that I, EUGÈNE HUREZ, a citizen of the French Republic, residing at Petit Couronne, near Grand Couronne, Seine Inférieure, France, have invented a new and useful Regenerative Furnace, of which the following is a specification.

This invention relates to an improved construction of the upright flues of a regenerative furnace such for instance as a coke oven of the usual type, in which each contiguous pair of flues is traversed by the gas originally in active combustion, and further on by the burned gases limiting thus to the minimum the heating zones of more or less intensity created by the reversing which has for its object to invert the direction of the gaseous currents in the respective pair of flues. The gas circulation is arranged so as to obtain automatically as uniform a distribution as possible of the combustion throughout each flue of the furnace. This condition is attainable by causing the gases of all the circuits to traverse a course exactly of the same length and resistance.

Nevertheless in spite of this theoretic equality, circuits may be more or less unequal in practice by reason of the gas eddies which for various reasons are liable to occur in the flues. In order to overcome these irregularities it is requisite that the proper quantities of gas and air be introduced and controlled in a precise manner and each separately, at the base of the flues, before they enter into combustion.

In this type of furnace, the dividing walls between each pair of contiguous flues form the special feature of this invention. These walls have such a construction that the heat evolved in the flues during the period of vigorous combustion is applied particularly to the heating of the walls of the coking chamber and as little as possible to the heating (which is pure loss) of the adjacent flues which convey the burned gases to the regenerators.

Referring to the accompanying drawings,

Figure 1 shows a vertical transverse section on the line 1—1 of Fig. 2 through the furnace, the flues and the regenerators.

Fig. 1^a shows an inlet flue and damper on an enlarged scale.

Fig. 2 shows an elevation and a partial section on the line 2—2 of Fig. 1 through the furnace, the flues, the gas inlets, and the

regenerators with parts broken away for greater clearness.

Fig. 3 shows a horizontal section on the line A—B of Fig. 2 and on an enlarged scale, of the insulating partitions forming an essential feature of my invention.

In the furnace shown in these drawings the gas for heating the flues is introduced at c and d (the latter serving as a compensating channel) and passes through the inlets k into the main gas flue between the hollow partitions.

Referring particularly to Figs. 1 and 1^a, the damper r usually closes only partially and seldom entirely the air admission conduit r'. It can never close the conduit k, being prevented by the little projection R².

Fig. 3 is a section on the line A—B of Fig. 2 and the damper r can close the conduit r' as shown in Fig. 3, for which purpose it moves in the direction of the arrow marked s on the drawing, being operated by means of a tool introduced through the upper part of the furnace through the removable plugs t when it is necessary to regulate the admission of the air. The gases arriving through c pass into the flues f, which flues form large passages, and the gases will not flow through the open space at the upper part of the structure by reason of the constriction of this latter.

The combustion gases pass at one time from the right to the left and at another time from the left to the right and the insulating spaces b of the partitions avoid the losses of heat from one side wall to the other as indicated farther on. The construction may be briefly summarized as follows:—

The furnace comprises a series of flues separated by partitions in each of which partitions there is provided a closed chamber b for the purpose of avoiding the losses of heat by transmission of heat from one wall to the other. In the flue e there arrives the gas from the inlet k and the air from the inlet r¹ necessary for combustion. This air supply can be more or less obstructed for control purposes by means of a valve r which is accessible from the top of the furnace through the movable plugs t. In these flues f the inlets of the gas and of the air supply both discharge. The special application here made of the principle, already known in itself, of an insulating air

space, to the purpose herein set forth is novel, and the following explanation will assist in demonstrating the technical effect obtained.

5 Taking two adjacent flues e, f . In the one e the gas enters into combustion at the lower part of the flue. In the other f the gas under combustion escapes from the flue also at the base. Consequently in the same horizontal section, a, b passing through these two flues, the gases are in a very different thermal condition in e, f , for in e the gas is at its maximum combustion, while at f it is at its minimum, the gas having given up its heat 10 to the walls of the furnace themselves cooled by the contiguous mass of coal under distillation. It is therefore desirable that the gases quitting the flue f shall not take away with them heat evolved by the combustion at e inasmuch as this heat must be utilized as far as possible for heating the walls of the coking chamber. If the partition between e and f were solid the heating 15 of the gas escaping from f would take place by reason of the conductivity of this partition. Further with regard to the question 20 of improving the useful heating of the coking chamber it is automatically realized by the same section of the partitions which in- 25 close the air shafts in question. For a given vertical flue, the exchange of heat between the gas and the coal to be distilled which lies on the other side of the furnace wall will be the more effective in accordance as the surface of interchange is proportionately larger 30 with reference to the surface over which the gas passes.

The operation of the coke oven constructed in conformity with the foregoing description 35 is in other respects similar to that of such regenerative furnaces in general. Here the gases during combustion rise in the flues $3, 3^1, 3^2$ and ascend in turn into the adjacent flues f, f^1, f^2 and then pass back to the corresponding regenerator. In the next following 40 period (about half an hour after the first) the flues f, f^1, f^2 receive the fresh com-

bustion gases and the flues e, e^1, e^2 discharge them after combustion.

What I claim is:

1. In a regenerative coke-oven of the type set forth the combination with means for controlling the combustion of gaseous fuel in the heating flue of said oven of insulating air space within the middle division of said flue, around which the evolved combustion heat travels to the distillation chamber.

50 2. In a regenerative coke-oven of the type set forth; a hollow partition in each flue around which the gases under combustion travel and means for regulating the quantity and the direction of flow of the air and the gas respectively through said flues.

55 3. In a regenerative coke-oven of the type set forth, a plurality of combustion flues, a hollow middle wall in each flue forming an entirely closed space adapted to act as a heat-conserving partition for the gases under combustion which flow over it, regulatable gas inlets into said flues, hot air supply inlets 60 into said flues and adjustable dampers 65 adapted to control the passage through the said flues of gases under combustion.

70 4. In combination in a regenerative coke-oven of the type set forth one or more divisions in the combustion flues of the coke-oven, each division comprising an inclosed chamber separating the sides of the division one from the other for the purpose of preventing heat interchange between the burnt 75 gases, and the gases undergoing combustion; in combination with two contiguous channels traversed the one by the gases in combustion and the other by the burnt gases, for the purpose of reducing to the minimum the heating zones occasioned by the reversal of 80 the gaseous currents.

85 In testimony whereof I sign my name to this specification in the presence of two subscribing witnesses.

EUGÈNE HUREZ.
